UNITED STATES PATENT OFFICE

154,880

DESIGN FOR A COMBINED BOTTLE CAP REMOVER AND CORK SCREW

Howard L. Ross, Greenwich, Conn.

Application February 25, 1948, Serial No. 144,723

Term of patent 3½ years

(Cl. D44—29)

To all whom it may concern:

Be it known that I, Howard L. Ross, a citizen of the United States of America and a resident of the city of Greenwich, in the county of Fairfield and State of Connecticut, have invented a new, original, and ornamental Design for a Combined Bottle Cap Remover and Cork Screw, of which the following is a specification, reference being had to the accompanying drawing, forming a part thereof;

Figure 1 is a side view of a combined bottle cap remover and cork screw showing my design.

Figure 2 is a top view thereof, and

Figure 3 is a front view thereof.

I claim:

The ornamental design for a combined bottle

cap remover and cork screw, substantially as shown.

HOWARD L. ROSS.
